G. L. FORT,
AUTOMATIC COLD METAL FEEDER FOR TYPE CASTING MACHINES,
APPLICATION FILED MAY 31, 1921.

1,412,856.

Patented Apr. 18, 1922.

UNITED STATES PATENT OFFICE.

GEORGE L. FORT, OF KANSAS CITY, MISSOURI.

AUTOMATIC COLD-METAL FEEDER FOR TYPE-CASTING MACHINES.

1,412,856.

Specification of Letters Patent. Patented Apr. 18, 1922.

Application filed May 31, 1921. Serial No. 474,054.

To all whom it may concern:

Be it known that I, GEORGE L. FORT, a citizen of the United States, and resident of Kansas City, county of Jackson, State of Missouri, have invented a certain new and useful Improvement in Automatic Cold-Metal Feeders for Type-Casting Machines, of which the following is a complete specification.

10 This invention relates to cold metal feeders for casting machines, especially line and type casting machines, and has for its object to produce a construction whereby the quantity of molten metal in the metal pot 15 of such machine, shall be automatically replenished and thermostatically maintained at a substantially predetermined level.

A further object is to produce a simple and efficient cold metal feeder attachment 20 susceptible of economical and ready application to any of the standard or approved types of metal pots now in use.

With these general objects in view, the invention consists in certain novel and useful 25 features of construction and combinations of parts as hereinafter described and claimed; and in order that it may be fully understood reference is to be had to the accompanying drawing in which:

30 Figure 1 is a fragmental view partly in elevation and partly in vertical section of the metal pot of a casting machine, and illustrates in operative relation thereto, a section of a feeder attachment embodying 35 the invention, the section being taken on the line I—I of Figure 2.

Figure 2 is a section taken on the line II—II of Figure 1.

Figure 3 is a horizontal section taken on 40 the line III—III of Figure 1.

Figure 4 is an inverted plan view of the attachment.

Figure 5 is an enlarged section taken on 45 the line V—V of Figure 1.

Figure 6 is a sectional perspective view of a modified form of the attachment.

In the said drawing, and referring particularly to Figures 1 to 5 inclusive, 1 indicates a metal pot of ordinary type used in 50 line and type casting machines, and 2 is the hood thereof from which the ordinary hinged door or lid is removed or omitted.

The attachment constituting the improvements comprises a base portion 4 hinged as 55 at 5 to the hood and taking the place of the ordinary cap or lid omitted as above re-

ferred to, by covering the opening 3 in the hood. In the preferred form of the invention the attachment is adapted for retaining a cold metal pig hereinafter identified, 60 in a vertical position so that through the weight of the pig, it shall be fed into molten metal in the metal pot. As shown a vertical guiding frame 6 is formed integral by preference, with the base 4, and is of rec- 65 tangular form in cross section. It is provided at each side with a vertical slot or opening 7 so as to leave for the greater part of its length, corner standards, and these standards at their inner sides are grooved 70 out to leave narrow tracks 8 which are machined so as to make them perfectly smooth where they come in contact with the metal pig 9, adapted in the preferred form, to be retained in a substantially vertical position 75 and fed by gravity through said retaining guide and holder 6.

As the pigs may not always be of standard cross sectional area so as to snugly engage all of the tracks 8, it may be found 80 advantageous to provide within the guide, suitable means whereby the pig may be adjusted so that its travel shall be undeviating, the means shown being a smooth plate 10 which is fitted between one side of the 85 guide and the pig. This plate is supported in position by a plurality of screws 11 extending through the wall of the guide, and such screws are supported in tubular bushings 12 threaded as at 13 into the guide. 90 By proper adjustment of said bushings the plate can be adjusted until it applies pressure flatwise against the adjacent face of the pig, and then the screws can be turned to clamp the plate tightly against the inner 95 ends of the bushings so that it shall constitute in effect a rigid part of the guide, without applying sufficient pressure on the pig to interfere with its free gravitational movement down through the guide and into the 100 molten metal of the pit, which contact melts the submerged end of the pig.

The base 4 of the attachment is provided in line with the opening 7 of the guide at the opposite side from the plate 10, with 105 an opening 14, and fitting therein and in the said registering opening 7 of the guide, is a clamp plate or brake 15, the same having a pin-and-slot connection with the guide as shown in Figure 1, so that it may be 110 moved toward and from the said plate 10, without chance of dislocation. An angle le-

ver 16 bears at its free end against the outer side of the brake 15 and extends up through an opening 17 in an outwardly projecting shelf 18 of the guide, the outer end of said 5 lever being fulcrumed on ears projecting upwardly from said shelf, as shown clearly in Figures 1 and 2. An adjustable screw or pin 19 is mounted in the lever and is secured at the desired point of adjustment 10 by means of a lock nut 20, and the lower end of said pin engages the upper end of a thermostat 21 projecting into a guide opening in the shelf, and extending down through the base 4 and into the pot to about 15 the normal or desired level of the molten metal therein, the lower end of the thermostat being held rigidly in place by means of a suitable yoke or brackets preferably cast with and depending from the said 20 base 4.

By reference to Figure 1 it will be seen that when the lower end of the pig is submerged in the molten metal of the pot, the former is subjected to a melting action, and 25 that when the heat is sufficient within the pot, as when the level of the molten liquid touches the lower end of the thermostat, the latter is expanded upwardly and applies upward pressure against the pin 19 and 30 thereby imparts movement to the lever to cause the brake 15 to apply pressure on and check further downward movement of the pig and hold the same in fixed position until sufficient molten metal has been withdrawn 35 from the pot to lower the temperature of the thermostat. When this occurs the temperature of the thermostat falls and when 40 this has progressed sufficiently, the pig begins to slip or feed downward, the recurrence of a sufficiently high temperature due 45 to an increase in the quantity of molten metal produced in the pot by the melting of the pig, immediately effecting the rearrest of the pig in its downward movement. 50 It has been found in actual practice that this thermostatic control is positive and reliable and results in the gradual feeding of the cold metal to the molten metal in the pot as needed and that it will continue as long as the pig is within the plane of engagement of the brake. When a pig passes 55 the brake another one is placed in the guide and the operations described are repeated.

In Figure 6, a modification of the attachment is shown, the guide in this instance being shown as cylindrical and composed of an upper member 23 and a lower member 24 detachably but rigidly suspended from the upper member and provided with an 60 inwardly projecting flange 25 at its lower end. This lower member in conjunction with a ring 26, enclosed within it and composed of different metal, constitutes a thermostat which is capable of variation in size 65 in only a single direction, that is to say in

internal diameter. It will be noted that the enclosing portion 24 of the guide, prevents enlargement of the ring 26, and that the latter cannot increase in length because of the underlying flange 25 and the overlying 70 lower end of the portion 23 of the guide. The inner ring of the thermostat being of metal more susceptible to heat than the outer, must yield in some direction, and as it cannot increase in length or increase in external diameter, its walls must thicken, and in increasing in thickness under the proper temperature, is adapted to grip and hold a cylindrical pig (not shown) fitted in the guide and through the thermostat thereof 80 and thus prevent the pig from moving downward. When the temperature falls sufficiently the said inner member of the thermostat will react and thus release its grip upon the pig and permit the latter to 85 feed downward into the molten metal of the pot. It will be apparent of course that there may be other types of thermostats substituted for either of those described without departing from the principle of 90 construction and mode of operation involved, and that it may be practical to dispose the pig in a position other than vertical, and utilize a force analogous to gravity, such as a spring, for advancing the pig into 95 the pot when the heat reaches a suitable degree. It will therefore be understood that I reserve the right to make such changes in the form, proportion, detail construction and arrangement of the parts as shall properly fall within the spirit and scope of the 100 appended claims.

What I claim is:

1. The combination with a metal pot containing molten metal and means for guiding a cold metal pig arranged for automatic advance, into contact with such molten metal, of thermostatic means for controlling the advance movement of the pig through the 105 said guiding means into the pot.

2. The combination with a metal pot containing molten metal and means for guiding a cold metal pig arranged for automatic advance, into contact with such molten metal, and thermostatic means for applying force against the side of the pig to arrest its advance movement and to relax such pressure when the thermostatic means cools sufficiently.

3. The combination with a metal pot, of 110 means for retaining a cold metal pig depending into said pot, in a substantially vertical position, and thermostatic means for controlling downward movement of the pig through the holding means into the 115 pot.

4. The combination with a metal pot of 120 means for retaining a cold metal pig depending into said pot, a thermostat depending into the pot, and means actuated 130

by expansion of the thermostat to arrest feeding movement of the pig into the metal pot.

5. The combination with a metal pot, guiding means for holding a cold metal pig depending into said pot, in a substantially vertical position, a thermostat depending

into said pot, a brake, and a lever actuated by expansion of the thermostat, to cause said brake to engage the pig and hold the 10 same against feeding movement.

In witness whereof I hereunto affix my signature.

GEORGE L. FORT.
